UNITED STATES PATENT OFFICE

WILLIAM M. NEISSL, OF CHARLESTON, ARKANSAS

TOOTHRUSH

Application filed October 15, 1928. Serial No. 312,669.

My invention relates to tooth brushes, and an object of the same is to provide a brush embodying a holder and a removable brush element, which may be readily removed and 5 cleansed after use.

Further, the invention provides a tooth brush embodying a flexible foldable brush element, which may be conveniently spread apart so that its entire surface may be 10 cleansed, thereby preventing bacteria from lodging between the rows of bristles as is now the case with the usual tooth brush.

With the preceding and other objects and advantages in mind, the invention consists in 15 the novel combination of elements, constructions and arrangements of parts and operations to be hereinafter more fully described, claimed and illustrated in the accompanying drawings, wherein:

20 Figure 1 is a side elevation of my improved tooth brush,

Figure 2 is a view, partly in front elevation and partly in longitudinal section, taken on the line 2—2 of Figure 1,

25 Figure 3 is a perspective view of the brush element embodied in the invention,

Figure 4 is a transverse section taken on the line 4—4 of Figure 2, and

30 Figure 5 is a transverse sectional view taken on the line 5—5 of Figure 1.

Referring to the invention in detail, a brush element is provided consisting of a longitudinal strip of flexible material 5, preferably rubber, having bristles 6 incorporated 35 therein and projecting from one edge thereof. As illustrated in Figure 3, the strip 5 is provided with a plurality of spaced transverse creases 7 to afford folds 8 which, when the brush element is in use, lie in superimposed parallel relation. While the brush element in this instance is formed in a single length, it may be formed from a plurality of small strips to be arranged in superimposed 40 relation.

45 For the purpose of holding the brush element in folded relation to afford a unitary brush surface, a holder is provided consisting of a resilient U-shaped handle 10 having crossed parallel jaws 11 and 12. At its forward end, the jaw 11 is formed with a right-

angular extension 13, which is normally abutted by the free end of the jaw 12. A substantially rectangular flange or wall 15 is formed with the jaw 11 and extension 13, and extends to the inner face of the jaw 12 ⁵⁵ and with the jaws constitutes a holder for the brush element.

In order to hold the jaws in clamping engagement with the brush element for use, the legs of the U-shaped handle are provided with ⁶⁰ oppositely extending lateral extensions 16. These extensions 16 are disposed in transverse alignment, and are located in advance of the point where the jaws cross. As particularly illustrated in Figure 4, the inner ⁶⁵ face of one of the extensions is provided with a plurality of serrations or teeth 17, while the inner end of the other extension is provided with an inwardly directed catch 18 adapted to engage in any one of the serrations, and thereby hold the legs of the U-shaped handle against springing apart.

When it is desired to remove the folded brush element, it is only necessary to move the legs of the U-shaped handle toward each other ⁷⁵ by exerting manual grip thereon. When the legs have been thus moved, they will laterally separate due to their resiliency, and consequently permit the jaws 11 and 12 to spring apart.

80 What is claimed is:

1. In a device of the character described, a resilient U-shaped handle member, crossed parallel jaws carried by the ends thereof, and latch means associated with the legs of the U- ⁸⁵ shaped handle slightly in advance of the points of intersection of the jaws to normally hold them against lateral separation and thus hold the jaws in position to clamp an object therebetween.

2. In a device of the character described, a resilient U-shaped handle member, crossed parallel jaws carried by the ends thereof, and co-acting normally interlocked latch elements carried by the legs of the U-shaped ⁹⁵ member adjacent the points of intersection of the jaws to prevent lateral separation of the legs and thereby hold the jaws in clamping relation.

3. In a device of the character described, a ¹⁰⁰

resilient U-shaped handle member, crossed parallel jaws carried by the ends thereof, a flange extending at right angles from one edge of one of the jaws and cooperating with such jaws in holding an object, and latch means associated with the legs of the U-shaped handle slightly in advance of the points of intersection of the jaws to normally prevent lateral separation of the jaws.

4. In a device of the character described a resilient U-shaped handle member the legs of which terminate in crossed extensions, cooperating jaws carried by the extensions, and normally engaged coacting latch elements carried by the legs of the U-shaped member at a point slightly in advance of the point of intersection of the crossed extensions and normally holding the jaws against lateral separation.
